WEB SLITTING AND CROSS PASTING APPARATUS

Rudolph P. Bechle, Yonkers, N. Y., assignor to Potdevin Machine Company, Teterboro, N. J., a corporation of New York

Application March 25, 1952, Serial No. 278,520

4 Claims. (Cl. 93—8)

My invention relates to an improvement in web slitting, and cross pasting mechanisms, and has for one of its objects to provide such mechanism which is economical, convenient and easy to adjust so as to adapt the same for use in the web slitting and cross pasting of multiple wall satchel bottom and self-opening paper bags.

Conventional bottoms formed on satchel bottom and self opening bags are slit so as to form bottoms with sufficient paste area and also so as to prevent the extreme inflexibility that results from the full angular fold.

The formation of a proper bottom is dependent upon the location and length of the slits.

It is essential therefore for optimum bottom-forming conditions that the slits be adjustable by the operator. It is equally essential that the slitting mechanism be consistent and reliable in operation. It must cut a clean slit of the right length and in the correct location both laterally and longitudinally of the web.

On multiple-wall bags it is considered advantageous, to reduce sifting, to stagger the slits in order to obtain a shingled effect. In this way a double seal is provided and the multiple walls are prevented from stiffening the bottom unduly. Staggered slits require that the slitting be done to both webs separately, that is before the webs are brought together and formed into a tube, but the relationship or relative location of these separate operations must be closely controlled and maintained.

I have found that the rotary shear principle of slitting is ideal for my slitting operation, in that I obtain clean cuts which are very consistent in location and length, all of which is very desirable in the modern high speed automatic machines employed in the making of bags.

My invention provides an apparatus in which the slitting is done substantially at paper speed, and provision has been made whereby paper speed and slitter speed are reconciled. The bag machines with which I am concerned are multi-size, that is, are capable of making bags in a variety of sizes, so that the web length between slits varies and the paper feed per revolution of the slitters also varies.

Prior to my invention the practice has been to employ knives and holders of proper diameter to match the circumference of revolution to the cut-off length of the bag in question. This has the obvious disadvantage of requiring a multiplicity of holders and knives for different bag lengths not to mention the time necessarily spent removing, installing, readjusting and retiming all of the components.

Furthermore provision must be made in the basic machine to accommodate this multiplicity of diameters with the attendant complication of drives, adjustments, etc.

The same problems to a somewhat lesser degree are involved in the cross pasting.

In my improved apparatus wherein the cutters and pasters are of fixed diameter, I accommodate the equipment to the making of bags of varying sizes by impart-

ing a pulsating cyclic motion to the slitters and cross pasters, the speed of the slitters varying from maximum to minimum and back to maximum on each revolution. The degree of speed variation from maximum to minimum is adjustable and is set so that at the maximum or minimum speed it is just sufficient to match the fixed diameter mechanisms to paper speed. The setting is such that pasting and slitting both take place at the same instant at the maximum or minimum point of the cycle.

In my improved apparatus one web is slit and cross pasted while the other is slit, the two webs then being brought together and combined. To reduce the necessary adjustments to a minimum I provide for the web lead from the slitter of one web to the point of combining the two webs to be equal to the distance from the point of combination of the two webs to the cross paster of the other web. This eliminates the necessity of adjusting the relative timing of these components when bag-sizes are changed.

Since cross pasting and slitting of the web must take place simultaneously because the speed is correct at only one point of the cycle, the web lead from the slitter to the cross paster must necessarily be an integral number of cut off lengths. Accordingly in order that provision be made to accommodate the machine to varying bag lengths I provide simple adjusting mechanism for this purpose:

The slitting mechanism essentially involves slitter shafts and anvil shafts, and the lateral adjusting mechanism I provide is such that the anvil shafts and slitter shafts are adjusted as a unit thus maintaining the proper shear relationship between the cutting edge.

For the cyclic drive for the slitters and cross paster I employ a crank motion although elliptic gears could be used but not to as good an advantage.

In the accompanying drawings wherein I have illustrated an embodiment of my invention.

Fig. 1 is a more or less diagrammatic fragmentary view of the two webs of a multi wall bag illustrating primarily the relative location of the web slits, cross pasting and cut-off;

Fig. 2 is a part sectional view illustrating the layout of the slitters and cross paster, etc.;

Fig. 3 is a top plan view in part section of the cyclic drive mechanism;

Fig. 4 is an end view of the same;

Fig. 5 is a fragmentary plan view in part section of the lateral adjusting mechanism for the slitting mechanism; and

Fig. 6 is an end elevation of the same.

Referring to Fig. 1 of the drawings, 2 and 4 designate two paper webs which are to be slit, cross pasted, combined and eventually formed into multi-wall bags.

These webs are being continuously advanced, and the slitting, cross-pasting, etc. take place while the webs are moving.

In Fig. 1, the slits in the web 2 have been designated 6, the cross pasting 8 is applied to the web 2 only.

The slits in the web 4 are designated 10. After the slitting and cross pasting operations the two webs are combined, and in a later operation, are cut into bag lengths. In order that the relation of the division of the webs into bag lengths to the location of the slots and cross pasting be illustrated, I have shown the transverse lines 12 on Fig. 1 as indicating the point of cut off.

Referring now to Fig. 2 of the drawings, the web 2 is taken from any suitable supply roll and is drawn through the machine in conventional fashion, it being borne in mind that, as is customary in bag making machines, the web is continuously moving at constant speed. In accordance with my invention the web as it comes into the machine passes around an idler roller 14 and from thence upwardly around anvil roller 16 which is simply driven

by the moving web. The web is then passed about idler rollers 18 and 20 to the cross pasting backing roller 22, idler roller 24, to pasting roller 26, whereby paste is applied longitudinally of the web, and where in fact the two web 2 and 4 are brought together or combined. This area will be referred to hereinafter as the combining station.

The web 4 is taken from any suitable supply roll and as it is drawn forward continuously it passes over idlers 28 and 30 and from thence about anvil roller 32, simply driven by the moving web, and then around idler roller 34 to the combining station.

While the two webs are moving forward at equal speed at all times they are travelling in separate paths to a point at least beyond the slitting and cross pasting stations.

The two webs after being slit and cross pasted, etc., are divided into bag lengths at 36.

As above explained the slitting and cross pasting of the web 2 are done simultaneously. Likewise as above pointed out these two operations are performed at paper speed. The means for accomplishing this will be described later in this description.

Inasmuch as the slitting and cross pasting of the web take place simultaneously, and inasmuch as the location of the slits and cross pasting of the web 2 has a definite relation to the area at which the webs are divided into bag lengths as shown in Fig. 1, it becomes necessary to provide some means whereby this relationship will be maintained when the spacing of division into bag lengths is altered to produce bag lengths of different lengths. I accordingly have provided for varying the length of lead or web between the anvil roller 16 and the cross pasting backing roller 22. As seen from Fig. 2 the web after it leaves anvil roller 16 passes about rollers 18 and 20 to the cross pasting backing roller 22, so that the web is in effect looped about 18. The shaft 38 of this roller, and on which the roller is rotatable, is provided at each end with a pinion 40 meshing with vertically extending racks 42. By rotating the shaft 38 by a handwheel, for instance, the roller 18 can be raised and lowered, thereby to vary the length of web between 16 and 22.

The cross paster is designated 42 and its cooperating tank roller is designated 44. The web 2 passes about the roller 22 which has been referred to as the backing roller for the cross paster 42 inasmuch as the cross paste is applied as the paster 42 is rotated past 22.

The slitters for the web 2 I have referred to as comprising an anvil roller 16 and a cooperating slitter roller, which in Fig. 2 I have designated 44.

The anvil roller 16 is provided with peripheral circumferential grooves 46, spaced at the desired intervals along the roller which depends upon the spacing of the slits 6 the roller which depends upon the spacing of the slits 6 transversely of the web. The slitting knives 48 carried by 44 are similarly spaced so that, with the two rollers rotating, the web as it passes between them will be slit with a shear cut. The anvil roller 32 and its cooperating slitter roller 50 for the upper web 4 are of similar construction.

Referring now to Figs. 5 and 6. As above pointed out it is necessary that each pair of anvil and slitter rollers be adjustable laterally of the web, and that one pair be adjustable relative to the other. This not only accommodates the machine to webs of different widths, but it enables the slits in one web to be staggered to any extent desired with respect to the slits in the other web. As above pointed out this staggering of the slits is desirable and of material advantage. In Figs. 5 and 6 I have shown the upper set of anvil and slitter rollers only, but it is to be understood that the lower set is similar in construction. Each of the members 32 and 50 at one end extends into and is rotatable relatively to an exteriorly threaded sleeve 52, these sleeves being threaded through the side frame 54 of the machine. Each sleeve 52 carries a gear 56 and these gears are in constant mesh with a wide faced gear 58 adapted to be manually rotated by knob 60. By rotating this knob it will be apparent that both the anvil roller and the slitter roller may be adjusted simultaneously laterally of the machine

and web. Inasmuch as the adjusting mechanism for the lower set of anvil and slitting rollers is a duplicate of that just described, it will be apparent that the two sets of rollers are adjustable relatively to each other.

As above pointed out the slitters and cross paster are given a pulsating cyclic motion. The slitter 44 is geared 1:1 to the slitter 50. Likewise these two rollers are geared 1:1 to the cross paster 42. Inasmuch as the circumferential grooves in each of the anvil rollers are continuous, the anvil rollers need not be driven other than by the paper web.

Referring to Figs. 3 and 4, the input and output shafts of the cyclic motion mechanism are designated 62 and 64, respectively, the shaft 64 being coupled to or integral with one of the slitter rollers or to the cross paster. Shaft 62 operates one revolution per bag and it revolves at a steady or constant rate. This shaft is keyed to gear 66 which is in mesh with a one to one gear 68. Gear 68 revolves on stud 70 which is in turn carried by housing 72. Housing 72 is arranged so that it can be moved through a limited arc and it is pivoted around the center of shaft 62 and gear 66. The center of gear 68 can be set concentric or at various degrees of eccentricity with respect to output shaft 64. Gear 68 carries driver 74 by means of stud 76. Driver 74 contacts, by slidable engagement, slide 78 which is in turn carried by and keyed to output shaft 64.

Gear 68 revolves at constant speed in time with input shaft 62 and driver 74 revolves in a circle concentric with gear 68 and with constant circumferential speed. In revolving it carries slide 78 along with it. However, if slide 78, and gear 68 are adjusted eccentrically, the lever arm, or radius from the slide center of rotation to the point of engagement with driver 74 varies from a maximum to minimum and back to maximum during the revolution. Since the driver circumferential speed is constant and the lever arm variable, shaft 64 is thereby driven with a variable angular velocity. The amount of speed variation is dependent upon the degree of eccentricity. Thus, by proper location of the adjustable housing the maximum and minimum speed of shaft 64 can be controlled by the operator. In the preferred form the housing is equipped with a dial indicating the proper eccentricity for the bag being run.

It is to be understood that changes may be made in the details of construction and arrangement of parts hereinabove described within the purview of my invention.

What I claim is:

1. In web slitting and cross pasting mechanism, the combination of pairs of slitting and anvil rollers adapted simultaneously to slit a plurality of webs moving in spaced paths, a shaft for each of said rollers to which the rollers are affixed, and means for laterally shifting each pair of slitting and anvil rollers relatively to the other slitting and anvil rollers, said shifting mechanism comprising an exteriorly threaded sleeve rotatably mounted on the shaft of each anvil and slitter roller, a machine frame through which the said sleeves are threaded, a gear affixed to each sleeve, an elongated gear meshing with the two last mentioned gears and means manually to rotate the elongated gear thereby to rotate said sleeves to move the slitter roller and anvil roller endwise.

2. In web slitting and cross pasting mechanism, the combination of pairs of rotatable slitting and anvil rollers adapted simultaneously to slit a plurality of webs moving in different planes, manually operated means for independently adjusting each pair of rollers transversely of the webs to accommodate webs of different widths and to stagger the slits in one web relatively to those in another web to any extent desired, a rotatable cross paster for cross pasting one web simultaneously with the slitting of the web, driving mechanism for the said slitting rollers and cross paster to impart to these elements a pulsating cyclic motion and to drive the slitters at a speed varying from maximum to minimum and back to maximum on each revolution, and means for varying

the setting of the driving mechanism to vary the maximum and minimum speeds of the slitters.

3. In web slitting and cross pasting mechanism, the combination of pairs of rotatable slitting and anvil rollers adapted simultaneously to slit a plurality of webs moving in spaced paths, manually operated means for independently adjusting each pair of rollers transversely of the webs to accommodate webs of different widths and to stagger the slits in one web relatively to those in another web to any extent desired, a cross paster for one web for cross pasting the web simultaneously with the slitting of that web, means located beyond the said slitting and cross pasting mechanisms for uniting the webs to provide a laminated structure, means for adjusting the lead of the cross pasted web between the cross paster and the said uniting means to equal the lead of another web between its slitter and said uniting means, driving mechanism for the slitter rollers and cross paster to impart to these elements a pulsating cyclic motion and to drive the slitters at a speed varying from maximum to minimum and back to maximum on each revolution, and means for varying the setting of the driving mechanism to vary the maximum and minimum speeds of the slitters.

4. In web slitting and cross pasting mechanism, the combination of pairs of rotatable slitting and anvil roll-

ers adapted simultaneously to slit a plurality of webs moving in spaced paths, manually operated means for independently adjusting each pair of rollers laterally of the webs to accommodate webs of different widths and to stagger the slits in one web relatively to those in another web to any extent desired, a cross paster for one web for cross pasting the web simultaneously with its slitting, an idler roller between the cross paster and slitter of the web last mentioned about which the web lead between slitter and cross paster is looped, and rack and pinion mechanism for shifting said idler roller to vary the length of the web loop thereby to vary the spacing of the slitting and cross pasting of the web.
